UNITED STATES PATENT OFFICE.

ROBERT H. LAWSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE MACHINE.

Application filed June 5, 1924. Serial No. 718,058.

This invention relates to machines for operating upon shoes, and especially to shoe machines by which fastenings are inserted, as those attaching heels or heel-portions, as bases or lifts. The illustrative embodiment of the invention herein presented is particularly adapted for the nailing rubber or other yieldable heels, either in the form of whole heels or top-lifts. It is not, however, limited

10 to this use.

An object of the invention is to provide means, which shall be both simple and effective, for performing such operations. Considering the invention in its broad aspect, a 15 fastening-inserting driver, or other operating tool, is movable in a carrier, as a fastening-holding tube, which carrier is itself movable, these movements of both elements being effected by connection between the tool and 20 an actuating member. By suitably joining the tool and carrier, as through a friction device, such mutual and independent movements may be obtained as will permit the carrier, under the influence of the tool, to first 25 bring the latter into correct relation to the work, and then to cause said tool to perform its operation. Herein the carrier is shown in the form of a pivoted tube, in which the tool operates. An actuating member is pivoted to the tool at a point spaced from the 30 pivot of the carrier along the path of movement of the tool, with the actuating member lying at an angle to said path. Through this arrangement, the applied force first acts to 35 swing the carrier about its pivot to position the tool, and when this movement is arrested, as by contact of a gage-portion of the carrier with the work, the continued pressure moves the tool in the carrier to cause its operation.

40 This operation may consist of driving a heel-securing nail which has been delivered to the carrier-tube by a conduit, and temporarily retained by means, as a nozzle, terminating the tube and being yieldable to permit the 45 nail to be forced through it by the driver.

The accompanying drawing illustrates a particular form of my invention designed to attach rubber-lifts. Here,

50 Fig. 1 shows, in perspective, portions of such a machine more essential to the present invention;

Fig. 2 illustrates, in a like manner, a rubber-heel as attached to a shoe by the machine;

Fig. 3 is a front elevation of the upper part of the machine, with the active portions 55 in section;

Fig. 4 is a central transverse section taken in a plane at right angles to Fig. 3; and

Fig. 5 shows, in perspective, one of the carrier-tubes and its support.

The frame of the apparatus, together with the operating and pressure-applying mechanism, may be generally that of the well-known lightning heeler, or as particularly illustrated in an application in my name, Serial 65 No. 690,054, filed February 11, 1924. Here, I have merely indicated a portion of the frame 10 carrying the die-block 12 and having, reciprocating vertically in it, the side rods 14, 14 with their connecting top girt 16. The 70 upper portion of a work-support or jack 18 is indicated below the die-block, this having, projecting upwardly from its top, spaced pins or projections 19 arranged to enter openings properly located in the heel-seat of a 75 shoe S, to which a heel is to be attached, alined openings in a heel-base H and depressions in a lift L. These projections hold the shoe, base and lift in predetermined relation to one another and to the nailing mechanism, 80 thus insuring the correct positioning of the heel-parts upon the shoe and the insertion of the nails at the desired points. From the center of the die-block, which is without the usual nail-openings, rises a standard or support 20, recessed at 22 to receive tool-carriers and nail-holders furnished by tubes 24. Of these tubes, five appear, one for each of the 85 attaching nails to be driven, except for an additional nail at the center of the heel-breast, 90 the inserting mechanism for which will be described later. Each of the tubes and its mounting is identical, save as to position, and but one of these will be considered in detail.

Projecting from the upper portion of the 95 standard 20 at each tube-position are brackets 26, in which are alined horizontal semi-cylindrical depressions 28 to receive trunnions 30 extending oppositely from the top of the tube. To hold the trunnions in the bracket-depressions, I provide a cover-plate 32 having registering depressions and secured to the top of the standard. Within the tube is the operating tool, in this instance a driver 34 having the customary cylindrical form. At its lower 105 end, the driver fits within a reduced bore 36

in the tube, while about its upper end is a bushing 38 arranged to slide in the tube-opening. This bushing surrounds the driver-holder 40, and has pivoted to it at 42 a link 44 passing through a vertical slot 46 in the carrier. The link is articulated at 48 to lugs depending from a plate 50 received in ways 52 in the top girt. The tube is free to swing between an inner position, in which it is substantially vertical, outwardly, the lower portion traveling through a slot 54 in the block 12 until it is arrested by contact with a plate 56 secured upon the top of the block by a slot-and-screw connection 58. The plate, variable in position by virtue of this connection, permits the limit of outward movement of the carrier to be changed. The tube has mounted upon it a friction device, in the form of a plug 60, movable through a horizontal bore 20 in a boss 62 and pressed inwardly into contact with the driver by a spring 64 abutting at its outer extremity against a screw 66 threaded into the boss-opening. Movement of the screw permits the tension of the spring, and thus the pressure exerted by the plug upon the driver to be varied. Observing that the pivotal connection 42 between the driver-carrier and link is below the pivotal support of the carrier by the trunnions 30, and that the link 30 44 is inclined downwardly and inwardly from the pivot 48 to the pivot 42, it will be seen that, assuming the carrier to be at the outer limit of its movement, downward travel of the actuating member or top girt 16 will first exert, through the link 44, a pressure upon the carrier, swinging it inwardly about the trunnions 30, the resistance to movement about the carrier-pivot being less than that exerted by the friction device acting through the plug 40 60 upon the driver. This movement continues until it is arrested by contact of a gage-surface upon the carrier with the heel-portion L which is to be attached. The gage is shown as consisting of a projection 68 depending from the outer side of the carrier at its lower extremity and having an inner vertical face 69 arranged to contact with the lift L as it is supported upon the shoe and base located by the pins 19. The carrier thus being positively held against movement, the plug 60 slips over the driver 34, so that continued downward travel of the top girt and link carries the driver through the tube for the insertion of the fastening. To adapt the apparatus to act at different distances from the periphery of the work, the projections 68 may be adjustable upon the carrier-tubes. In the present instance, they are shown as mounted on springs 71 secured to the tubes at their upper extremities. The tendency of these springs is to urge the projections outward. Their locations may be varied, however, by screws 73 threaded into the tubes and with their heads bearing against the springs.

65 At the lower portion of each tube is a down-

wardly, inwardly inclined passage 70 converging toward and entering the bore 36. Nails N are delivered in successive charges to this and the passages of the associated carriers through flexible tubes 72 from a distributor 74 carried upon the frame 10 at the rear of the machine. This distributor may be of any suitable type, as that illustrated in Patent No. 1,005,303, Pope, Oct. 10, 1911. To retain the nails to receive the action of the drivers, each tube has associated with the delivery-opening, below the junction of the passage 70 with the bore 36, a nozzle 76, formed in halves divided vertically. These sections of each nozzle are located in opposite vertical recesses 78 at the sides of the carrier-tube, and have at their upper and lower portions angular ends 80, the upper of which lie in transverse recesses 82, while the lower move across the end of the tube. The engagement between the end-portions 80 and the tube is such as to permit oscillation of the sections about the upper positions as pivots, while the lower portions furnish guides in this movement. At the bottom of each nozzle-section is a rounded delivery-end 84, through which is a contracted passage 86, axially aligned with the bore 36. The nozzle-sections are normally held together, with the delivery-opening of the passage so contracted that a nail supported within it will be retained, by a spring 88 of the scissors type, with its convolutions encircling a pin 90 carried in lugs 92 upon the gage member 68. The arms 94 of this scissors-spring bear against the outer sides of the nozzle, holding them yieldably together.

In using the apparatus for the attachment of a rubber-lift, the shoe S, with the heel-base H previously secured thereto and both provided with locating openings, may be placed upon the jack 18 with the pins 19 within the openings, and the lift L located upon the base by the engagement of the pins with its depressions. Upon the upward movement of the top girt from the preceding nailing operation, the distributor 74 was tripped in the usual manner, delivering a charge of nails to the conduits 72. Falling through the conduits and passages 70, these nails enter the bores 36, and are held with their points downward by the sections of the nozzles 76 closed by the springs 88. The carrier-tubes 24 are at this time against the stop-plates 56 as a result of the upward movement of the top girt, the links 44 having first swung out the carriers 24 about their trunnions 30, after the pressure upon the work had been released by the descent of the jack, until they were stopped by the plates 56, the friction at the plugs 60 thereafter slipping to allow the full elevation of the drivers. Thus, for each operation, the carrier-tubes are found separated to their full extent, adapting them to engage the periphery of whatever size lift is to be attached. When the

machine is started for the current operation, the descent of the top girt initially causes the pressure of the links 44 to carry the gage-positions 68 of the carriers into contact with the edge of the lift, the friction at 60 resisting movement of the drivers. By this engagement with the work, each of the nozzles 76 is located at the correct distance from the periphery of the heel for the insertion of the nail which it carries. The space between the delivery-opening 86 of each nozzle and its corresponding gage-surface 69 is arranged to determine this. The position of the nozzles with reference to the lift having been thus gaged, the engagement of the contact-surfaces stops the movement of the carriers, and the slipping of the frictional connections allows the descent of the drivers under the influence of the links, they striking the heads of the nails supported in the nozzles and driving them through these, the sections opening to permit their passage into the lift and base to attach the former.

The nail which is inserted at the center of the breast of the heel, on account of its relation to the locating pins 19, is preferably driven in the same position for all sizes of heels. Consequently, the driver 96 for this nail may be connected directly to the plate 50 at 98 and operates within a passage 100 formed in the support 20. The passage 70, through which nails are delivered from the distributor to receive the action of this driver, and the nozzle 76, which terminates it, may be the same as these elements already described in connection with the oscillatory drivers.

Having described my invention, what I claim as new and desire to secure by Letters Patent of the United States is:

1. In a machine of the class described, a tool for operating upon the work, a carrier in which the tool is movable, said carrier being movable to change the relation of the tool to the work, an actuating member, and connections between the actuating member and tool to move said tool and thereby the carrier.

2. The combination with a tool for operating upon the work, of a carrier in which the tool is movable, said carrier being movable to change the relation of the tool to the work, an actuating member, connections from the actuating member to move the tool independently of the carrier and said carrier and tool together, and a friction device joining the tool and carrier and arranged to cause such simultaneous movement while permitting independent movement.

3. The combination with a pivoted carrier, of a tool movable in the carrier into and out of co-operation with the work, and an actuating member pivotally connected to the tool and operable to cause said movement, such pivotal connection being situated at a

point spaced from the pivot of the carrier 65 along the path of movement of the tool and with the actuating member lying at an angle to said path.

4. In a machine of the class described, a tool for operating upon the work, a carrier 70 in which the tool is movable, said carrier being movable to change the relation of the tool to the work and having a gage-surface for contact with said work, means arranged to vary the position of the gage-surface upon 75 the carrier, an actuating member, and connections between the actuating member and tool to move said tool and thereby the carrier.

5. The combination with an oscillatory 80 carrier, of a tool mounted to reciprocate in the carrier, and an actuating member arranged to reciprocate the tool and oscillate the carrier and to apply the actuating force 85 in a direction inclined to the path of movement of the tool.

6. In a machine for inserting fastenings, a movable fastening-holder, a fastening-inserting member movably mounted in the holder, and connections directly to the inserting member arranged both to move the holder and to impart to said member its inserting movement.

7. In a machine for inserting fastenings, 95 a movable fastening-holder, a fastening-inserting member movably mounted in the holder, connections to the inserting member arranged to move both the holder and said member, and a friction device carried by the holder and engaging the inserting member. 100

8. In a machine for inserting fastenings, a movable fastening-holder, a fastening-inserting member movably mounted in the holder, connections to the inserting member arranged to move both the holder and said member, and a fastening-conduit in constant communication with the holder. 105

9. In a machine for inserting fastenings, 110 a movable fastening-holder, a fastening-inserting member movably mounted in the holder, connections to the inserting member arranged to move both the holder and said member, a fastening-conduit delivering to the holder, and means arranged to retain the fastening in the holder to receive the action 115 of the inserting member.

10. In a machine for inserting fastenings, a movable fastening-holder provided with a gage-surface, a fastening-inserting member movably mounted upon the holder, and connections to the inserting member arranged to first move the holder to bring the gage-surface into contact with the work and thereafter to actuate the member to insert the fastening. 120

11. In a machine for inserting fastenings, a movable fastening-holder provided with a gage-surface, a fastening-inserting member

movably mounted upon the holder, an actuating member, connections between the actuating member and inserting member, and a friction device connecting the inserting member and holder.

12. In a heel-attaching machine, a support, tubes pivoted thereon, drivers arranged to slide in the tubes, a reciprocatory actuating member, and links connecting the actuating member and drivers and organized to move the tubes upon their pivots.

13. In a machine for inserting fastenings, a movable fastening-holder, a fastening-inserting member movably mounted in the holder, a gage member adjustable upon the holder, and connections to the inserting member arranged to move both the holder and the fastening-inserting member.

14. In a heel-attaching machine, a support, tubes pivoted thereon and arranged for independent movement upon their pivots, drivers arranged to slide in the tubes, a reciprocatory actuating member, connections between the actuating member and drivers, and nail-conduits connected with the tubes.

15. In a heel-attaching machine, a support, tubes pivoted thereon, drivers arranged to slide in the tubes, a reciprocatory actuating member, connections between the actuating member and drivers, nail-conduits connected with the tubes, and yieldable nozzles terminating the tubes and acting to temporarily retain the nails delivered by the conduits.

16. In a heel-attaching machine, a support, tubes pivoted thereon and having delivery-openings, drivers arranged to slide in the tubes, a reciprocatory actuating member, and links connecting the actuating member and the drivers between the pivotal points of the tubes and the delivery-openings.

17. In a heel-attaching machine, a support, tubes pivoted thereon, drivers arranged to slide in the tubes, yieldable pressure members carried by the tubes and engaging the drivers, an actuating member, and connec-

tions between the actuating member and drivers.

18. In a heel-attaching machine, nail-driving mechanisms each including a tube provided with a gage-portion and a driver movable in the tube, and a member movable to carry the gage-portion into contact with a heel to be attached and to operate the drivers.

19. In a heel-attaching machine, a support, tubes pivoted thereon and having gage-portions, drivers movable in the tubes, a reciprocatory actuating member, and connections to the actuating member arranged to carry the gage-portions into contact with the heel to be attached and to operate the drivers.

20. In a heel-attaching machine, nail-driving mechanisms each including a tube provided with a gage-portion and a driver movable in the tube, and means connected to the drivers to actuate them and carry the gage-portions of the tubes into contact with a heel to be attached.

21. In a heel-attaching machine, a support, tubes movable thereon, drivers arranged to slide in the tubes, springs secured to the tubes, gage members carried by the springs, adjusting screws co-operating with the gage members, and means for actuating the drivers.

22. The combination with a movable tube provided with a gage-portion arranged for contact with the work, of a tool movable in the tube, and a member movable to carry the gage-portion into and out of contact with the work and to operate the tool.

23. In a machine for operating upon heels, a movable tube provided with a gage-portion arranged for contact with the heel-portion of a shoe, a tool movable in the tube, and means connected to the tool to operate said tool and carry the gage-portion toward and from the shoe.

In testimony whereof I have signed my name to this specification.

ROBERT H. LAWSON.
